CLAIM

The ornamental design for an IP phone, as shown and described.

DESCRIPTION

FIG. 1 is a front view of an IP phone showing our new design;

FIG. 2 is a top view thereof;

FIG. 3 is a bottom view thereof;

FIG. 4 is a right side view thereof;

FIG. 5 is a rear view thereof;

FIG. 6 is a left side view thereof;

FIG. 7 is a right front perspective view thereof;

FIG. 8 is a left front perspective view thereof;

FIG. 9 is a left rear perspective view thereof, shown without the handset for ease of illustration; and,

FIG. 10 is a right rear perspective view thereof, shown without the handset for ease of illustration.

The broken line showing of environmental structures is for illustrative purposes only and forms no part of the claimed design.
